United States Patent Office.

MILTON SATTERLEE, OF RICHLAND CENTRE, WISCONSIN.

Letters Patent No. 84,379, dated November 24, 1868.

IMPROVEMENT IN SLEIGH-BRAKE.

The Schedule referred to in these Letters Patent and making part of the same.

To all whom it may concern:

Be it known that I, MILTON SATTERLEE, of Richland Centre, in the county of Richland, and State of Wisconsin, have invented a new and improved Sleigh-Brake; and I do hereby declare that the following is a full, clear, and exact description of the construction and operation of the same, reference being had to the annexed drawings, making a part of this specification, in which—

Figure 1 is a side elevation.

Figure 2 is a cross-section.

This invention is a neat, cheap, and easily-operated adjustable brake, which can readily be attached to any sleigh or sled.

In the drawings, A represents the runners, B the top, and c c c, the studs of an ordinary sleigh.

Between two of the studs, I attach to the runner and top an upright post, D; and in a slot in the upper end of this, by means of a set-screw, bolt, and nut, d, I pivot my brake-attachment, in such a manner that the brake can be adjusted up or down at pleasure, in order to make it come more or less in contact with the hard surface of snow or ice beneath.

The brake itself consists of a stout spur-wheel, w, supported between two arm-plates, e e', the latter of which is attached to the former by the screw-bolt i, and by the journal m of the wheel, the former supporting both the wheel and the outer arm-plate, and being itself pivoted, as above described, on the bolt d.

The inner or supporting-plate e also has an arm, n, which projects upward and forward, for the purpose of connecting with the separating-lever near the driver's seat.

s is a pin, which prevents the arm-plate from moving too far backward when the brake is put on, and J is a guard, which may be attached to the runner for the same purpose, as well as to steady the brake, and prevent it from springing off from the runner by force of the snow, and wedging behind it.

The means for operating this brake consist simply of the ordinary lever, L, and rod, R, the latter operating a bell-crank, T, which is connected with the arm n by a rod, r.

By throwing the lever L forward, the brake is raised, and, by throwing it backward, it is depressed, and caused to come in contact with the ground, and to arrest the motion of the sleigh.

The device has been thoroughly tested practically, and is found to operate admirably, arresting the motion of the sleigh, not in a rough, jerking manner, but gently and easily, and keeping itself entirely clear of snow and ice. It can be attached to any form of sleigh or sled, whether single or double. When used with the latter form, I usually attach it to one of the rear runners.

Having thus described my invention,

What I claim as new, and desire to secure by Letters Patent, is—

The combination of the arm-plates e e' with the spur-wheel w, and the means for raising or depressing it, when used as a brake in connection with a sleigh or sled, in the manner described.

MILTON SATTERLEE.
